TELEPHONE ASH TRAY

William L. Coulter, Dallas, Tex.

Application August 29, 1952, Serial No. 21,236

Term of patent 7 years

(Cl. D85—2)

To all whom it may concern:

Be it known that I, William L. Coulter, a citizen of the United States of America, residing at Dallas, in the county of Dallas and State of Texas, have invented a new, original, and ornamental Design for a Telephone Ash Tray, of which the following is a specification, reference being had to the accompanying drawing, forming a part thereof.

Fig. 1 is an edge elevational view of a telephone ash tray showing my new design;

Fig. 2 is a side elevational view thereof, taken at right angles to that shown in Fig. 1;

Fig. 3 is a top plan view thereof;

Fig. 4 is a side elevational view thereof, showing the side opposite that shown in Fig. 2; and Fig. 5 is a perspective view thereof.

I claim:

The ornamental design for a telephone ash tray, as shown.
